CRUSHING MACHINERY

Sheldon Stearns, Westfield, N. J.

Application August 27, 1935, Serial No. 38,016

9 Claims. (Cl. 83—10)

My invention relates to improvements in crushing machinery, in particular to the type of crushing machinery known as gyratory crushers.

In a gyratory crusher there is usually a centrally located conical crushing or breaking head mounted upon a vertical shaft. One end of this vertical shaft is gyrated by means of an eccentric driven directly or indirectly by a motor. The other end of the shaft is centrally and pivotally mounted. Surrounding this conically shaped head are stationary concaves or crushing surfaces so shaped as to form a large entrance opening between the conical head and the concaves at the top, and a continuously narrowing space between the head and the concaves towards the lower or discharge end. The shaft and head do not revolve, but are so gyrated that the head moves towards and away from the concaves at every point of its circumference, once for every revolution of the eccentric. The minimum clearance between the heads and the concave at the discharge end is set to produce a crushed material to some definite and desired size or fineness. Material to be crushed is introduced at the top or entrance opening between the head and concaves, and as it is gradually crushed to size, due to the gyrating motion of the head, it drops and is finally discharged from the lower or discharge end of the crusher.

In practice I have found that frequently packing or choking of the material to be crushed occurs as the material approaches the smaller clearances between the gyrating head and the concaves at or near the discharge end of the crushers. This packing of material produces heavy stresses in the crushers, sufficient at times for parts of the crusher to break due to this heavy stress, in spite of the fact that provisions usually are made to increase automatically and momentarily the smaller clearances between the head and the concave when such high pressures occur. To accomplish this the frame holding the concaves is held in a stationary position by compressed springs which under high loads, such as occur when the crushing material begins to pack, compress still further and permit the concaves to move vertically upward and increase the clearance between them and the gyrating head. Another method used for relieving the pressure of high stresses is to have the concaves held stationary and to permit the shaft carrying the gyrating head to move vertically downward so as to increase the clearances between the concaves and the head. When such automatic adjustments of either the concaves or head occur,

the material crushed is no longer of uniform fineness, but is coarser due to the increase of minimum clearance. By resorting to the above means of relieving the pressures, which are caused by packing of the material between the crushing surfaces, inefficiency of crushing results on account of the cushioning effect due to the use of springs supporting the main crusher shaft, or springs so arranged to allow the frame supporting the concaves to move vertically upward. This necessarily increases the power required to drive the crusher. However, in spite of the precautions taken to automatically relieve the crusher of the high stresses due to packing or choking, important parts of the crusher wear rapidly requiring expensive renewals, and parts frequently fail.

My invention consists in so designing and constructing the gyrating head and concaves that the crushing is performed in certain definite stages or steps.

The first crushing stage serves to crush the material from its original size to some definite intermediate size. It is then discharged from the first crushing stage and allowed to enter a second crushing stage. Two or more stages are used for crushing the material from its original size to the desired finer size. The crushing stages are so arranged that the material in passing from any crushing stage is received in a succeeding stage having a considerably greater crushing surface than that of the preceding crushing stage. The discharge space between the concaves and the crushing heads of the first stage is so designed that it does not pass more material at that point than can be accommodated or crushed during an equal interval of time in the second crushing stage. If the crushing of a material is accomplished in more than two stages, the discharge space of each crushing stage is so proportioned that it does not pass more material than can be crushed in an equal interval of time in the succeeding stage.

In other words, in the present type of gyratory crusher, especially when making large reductions in the sizes of the material to be crushed, there is no control of the flow of material from the time it enters the receiving opening of the crusher until it reaches the discharge end of the crusher. Whereas in the crusher of my invention, in which the crushing is performed in stages, I have controlled crushing by so proportioning the discharge opening of each stage that it cannot discharge more material than can be accommodated in the succeeding stage, thus obviating entirely any

choking or packing of the crushed material so frequently occurring in the present types of fine reduction crushers.

The present types of gyratory crushers may be classified as either coarse crushers, medium crushers, or fine reduction crushers. When it is desired to crush coarse material to a fine size, two or three separate crushers are sometimes employed, the final fine crushing can also be done in grinding machinery such as ball mills or rolls.

10 Crushers according to my invention can crush in a single unit, a coarse material to a fine material, where heretofore such reductions had to be made in more than one crushing unit. By
15 crushing the material in stages I virtually control the flow of the material at certain definite points throughout the crushing operation. The amount of material flowing from one crushing stage to another is entirely controlled by the discharge
20 opening between the head and concaves of each stage. The proper choice of such control points depends upon the kind of material to be crushed, as for instance, its hardness or friability. Should the amount of material passing from one crush-
25 ing stage to another be greater than the latter stage can accommodate without choking or packing, it is only necessary to reduce the discharge opening of the previous stage by adjusting or inclining the head or the concaves to such an extent that the previous stage will not discharge
30 more material than the succeeding stage can crush and discharge without packing.

Another important advantage in crushing material in definite stages is the ease in which the crushing areas or surfaces can be greatly increased in any given stage over that of the preceding stage. For a given quantity of material much greater crushing areas or surfaces are necessary as the material approaches its reduced size than when it is in a coarse form.

40 For example, in the present type of gyratory crushers having a diameter at discharge end of say three feet, eighty tons of a certain material can be crushed per hour to one inch size. If this
45 same crusher is to crush the same material to one-half inch size by readjusting the discharge opening, only forty tons of material per hour can be crushed, and if the discharge opening is set to produce a material of one-quarter inch size, the capacity of the crusher drops to twenty-five tons per hour. Therefore it can be seen that although the upper part of the crushing surfaces of this gyratory crusher is capable of handling eighty tons of material per hour, the intermediate and lower crushing zones of the crusher
50 are only capable of handling a much smaller quantity of material per hour. This means that the crusher can deliver more material to the intermediate and discharge zone than can be handled by them, and as a result under these
55 conditions, the material frequently chokes or packs towards the discharge end of the crusher causing undue strains and excessive power consumption.

65   However, in the crusher of my invention, if the first crushing stage is made to crush eighty tons of material per hour to one inch size, the head and concaves being made about three feet in diameter at the discharge end, and if the second stage is to crush this material to one-half inch size, the head and concaves are made about four feet in diameter. If this same material is to be crushed to one-quarter inch size, a third crushing stage is used having a diameter of head and concaves considerably larger than the pre-

vious stage so as to have a capacity sufficient to take care of the original quantity of material passing through the preceding stages of the crusher.

The above data is given only as an illustration, but in the actual designing of a multi-stage crusher according to my invention, reductions made in each stage and the various diameters necessary for the head and concaves must be determined by the designer to suit the actual requirements. 10

Another advantage of my invention lies in the fact that if the crushing is performed in definite stages each stage can be designed with nearly vertical crushing surfaces. It can readily be understood that the more nearly vertical the crushing surfaces are, the more readily will the material pass through the crusher by gravity. In the present types of gyratory crushers the desire to greatly enlarge the area of crushing towards the discharge end resulted in inclining the crushing surfaces at a considerable angle from the vertical, which retards the gravity flow of the material, and if inclined too much causes packing.

A further advantage of my invention lies in the fact that if the crushing is performed in definite stages in which each stage does not discharge more material than can be accommodated in the succeeding stage, thus eliminating choking and packing, the power required for crushing is reduced to a minimum. 25 30

For a more detailed understanding of my invention reference is to be made to the following description and the accompanying drawing of 35 practical embodiment of the inventive idea, and in which drawing the figure is a part sectional view of a gyratory crusher showing particularly the gyratory head and concaves.

Referring to the figure the electric motor for driving the crusher is shown at 1. This motor drives the vertical shaft 2 through the coupling 3. The lower end of the vertical shaft 2 is keyed and fastened to an eccentric bushing 4. The outer surface of the eccentric bushing is journaled in a stationary frame 5, and the inner surface of the eccentric bushing rotates about the hollow gyrating shaft 6. This hollow gyrating shaft permits the driving shaft 2 to pass through it without contact and carries the crushing heads 7, 8 and 9 on its enlarged tapered portion. The gyrating shaft 6 near its upper end is centered and pivotally mounted in a ball seated bearing 10, and is supported at its threaded upper portion by the nut 11. The motor 1 in turning the shaft 2 rotates the eccentric 4, which in turn oscillates the gyrating shaft 6 about its upper and centrally located pivot 10. The weight of the motor and all the rotating and gyrating parts is carried by the spider casting 12 mounted upon the stationary frame 13. This frame is suspended by a number of suspension wire ropes 14 from a fixed support above the crushers and not shown in the figure. Surrounding the crushing heads 7, 8 and 9 are stationary concaves 15, 16 and 17. These concaves are arcuate in form and when properly mounted in the supporting frame 13, a number of them will form a complete circular stationary crushing surface around each of the gyrating heads 7, 8 and 9. The usual number of concaves to a complete circular set consists of from five to fourteen separate castings, depending upon the size of the crusher, but when conditions require it, a continuous ring casting may be used in place of the more usual design of concaves. All 75

concaves, including ring concaves, can be backed with zinc as is usual in all types of gyratory crushers.

As shown in the figure the space between the crushing heads and their corresponding concaves is larger at the top than at the bottom or discharge end. Material is introduced into the space at the top between the crushing head 7 and the concaves 15 and is crushed to the size of the minimum clearance between the head and the concaves at the discharge end. The material is then guided by the sloping surfaces 18 of the crushing head and 19 of the frame into the enlarged receiving opening of the next crushing stage, that is, into the upper part of the space between the head 8 and the concaves 16. In the space between the crushing head 8 and concaves 16 the second stage of crushing is performed. The minimum clearance at the bottom of this space is less than the minimum clearance in the first crushing stage. The material after being discharged from the second crushing stage is again guided by the sloping surface 20 of the gyrating head and the sloping surface 21 of the frame to the entrance of the third crushing stage, that is the space between the crushing head 9 and concaves 17. The minimum discharge opening between the third crushing head 9 and the third set of concaves 17 is made so as to deliver the crushed material of the desired size or fineness. Obviously, therefore, to provide in a crusher according to my invention, a structure wherein each stage can not discharge more material than can be handled by the next succeeding stage, the discharge openings of all of the crushing stages must have approximately equal active discharge areas. The material upon being discharged from the last crushing stage drops upon the inclined surface 22 of the frame and is discharged through a suitable opening 23 of the frame of the crusher. As clearly shown in the drawing, the inclined guiding or conveying surfaces 18 and 20 are formed on the gyrating crushing head and move therewith, for shaking the material as it passes from one stage to the succeeding stage, thereby aiding gravity action in distributing the material into the inlet of the succeeding crushing stages. Also as clearly shown in the drawing, these conveying surfaces 18 and 20 are inclined at much smaller angles to the horizontal than are the inclined surfaces of the crushing heads 7, 8 and 9.

The crushing surfaces both of the head and of the concaves are made of a hard and wear-resisting material, such as manganese steel. The crushing heads shown in the figure consist of cast iron or cast steel head centers mounted on the main gyrating shaft and having manganese steel zinned mantles mounted on the head centers and held in position with the necessary locking devices. If the crusher shown in the figure is used for crushing hard and abrasive material, the conducting surfaces from one crushing stage to the succeeding crushing stage 18, 19, 20 and 21 should be made of wear-resisting material.

The proper choice of minimum crushing openings of all the crushing stages preceding the last crushing stage depends largely upon the kind of material to be crushed and also whether the material is crushed wet or dry.

Stage crushing, according to my invention, permits the introduction of water into any of the later stages of the crushing operation, when it is found desirable to do so. This cannot be done in

a practical manner in the present type of gyratory crusher, especially in a fine reduction crusher.

It will be noted that the crushing heads of each stage in the figure extend slightly below the bottom of the corresponding concaves. This is the usual practice so as to permit compensating for wear of the crushing surfaces by slightly raising the entire crushing head. Should, however, too much material be discharged from any crushing stage into the succeeding crushing stage so that the latter cannot take care of the material in its stage, it is only necessary to decrease the minimum clearance of the preceding stage so that less material will pass that point, and by this means obviate the choking or packing of the material in the succeeding stage. Decreasing the minimum clearance in any one crushing stage necessitates only resetting the concaves so as to form a circle around the crushing head of a slightly smaller diameter or in an extreme case of replacing the concaves in such a crushing stage by another set of concaves setting closer to the head. It is also possible to replace the head mantle to accomplish the same results. In any crushing stage the larger part of the wear usually takes place at the discharge end. In a crusher of my invention it is possible to so design the crushing surfaces of the segmental concaves or ring concaves of any stage so that they may be reversed in such a manner that the worn surface of the discharge end is placed at the top and the less worn surfaces of the top are now placed at the bottom, thus allowing double wear of the crushing surfaces of the concaves, and obviating too frequent renewals of the concaves.

As has been mentioned before, any material to be crushed requires more crushing surface or area as the material is reduced to a smaller size because the voids are greatly reduced. In the figure, it should be noted the ease with which the crushing surfaces or crushing areas can be greatly and quickly increased from stage to stage and still retain the crushing surfaces in each crushing stage in a nearly vertical position. This permits the material being crushed to drop more rapidly between the crushing surfaces.

Referring to the figure, I obtain control crushing by being able to adjust the discharge opening of each crushing stage. If too much material flows from one stage to another, the discharge opening of the former crushing stage in question is made smaller, and if less material is discharged from the stage than can be accommodated in a succeeding stage, the discharge opening of the previous stage can be increased so as to permit a greater flow of material.

I have called attention to the fact that my invention necessitates all crushing stages to crush the same quantity of material in equal intervals of time. This requires making the discharge areas of all stages such that they will permit the same weight of material to pass through them in an equal interval of time. For example, let us consider two-stage crushing in a gyratory crusher in which the first stage is to have a minimum discharge opening between head and concaves of $\frac{1}{2}$ inch, and that the diameter of the gyrating head at the discharge point is 33 inches. Taking the eccentricity of the gyrating head at this point to be $\frac{1}{4}$ inch, the diameter of the opening of the concaves at the discharge point will then be $34\frac{1}{4}$ inches. The area of the head at this point is 855.3 sq. in., and the area of the opening of the concave at this point is 921.3 sq. in., the dif-

ference of these two areas, 66 sq. in., is the area of the discharge opening of the first stage. This discharge area will pass a certain weight of crushed material. At any instance, only a part of the discharge area extending around part of the circumference of the head is discharging crushed material, while the remaining area is discharging very little material because crushing of the material is taking place. Suppose it is found that 70% of the discharge area is actually discharging crushed material at any instance, then 70% of 66 sq. in. gives 46.2 sq. in. active discharge area.

Corrections of discharge area must also be made to take into account the percentage of voids existing in the crushed material; and also corrections must be made taking into account the number of gyrations of the head per second, because each gyration of the head stops and then permits again the movement of material through the discharge opening by gravity, thus limiting the free gravity flow of the material. Corrections also must be made as to the influence of the inclination from the vertical of the crushing surface of the head, as its frictional resistance to the material interferes with the acceleration of the material due to gravity.

Suppose all of these corrections reduce the weight of material discharged to that which would be discharged continuously by an equivalent opening of 40 sq. in.

Now let us suppose the second stage is to have a minimum discharge opening of $\frac{1}{8}$ inch, and that the eccentricity of the gyrating head at the discharge of this second stage is $\frac{3}{8}$ inch. If the diameter of the second stage gyrating head at the discharge is 46 inches, then the diameter of the concaves at this point will be 47 inches. The area of the head at 46 inches diameter is 1662 sq. in. and the area of the opening of the 47" diameter concave is 1735 sq. in., then the discharge area is 73 sq. in. If 60% of this area is actually discharging material at any instance, then 60% of 73 sq. in. gives 43.8 sq. in. as the active discharge area.

Suppose all the other corrections mentioned above, reduce the weight of material discharged to that which would be discharged continuously by an equivalent opening of 40 sq. in., then the second stage of this crusher will discharge the same quantity or weight of material as is discharged by the first stage.

It is, of course, obvious that although three stage crushing is shown in the drawing, those skilled in the art can apply my invention to only two stage crushing or to multiple stage crushing, having more than three stages. It is also obvious that those skilled in the art can apply my invention to various other types of crushing machinery.

In the crusher of my invention it may also be desirable to have a number of peep or hand holes located ninety degrees apart below the bottom of the concaves of each stage. These are not shown on the drawing. They are to be used for inspecting and determining the opening between head and concaves at the discharge end of each crushing stage.

In a crusher according to my invention it may be found desirable to crush the material dry in the early crushing stages and wet in the succeeding crushing stages, and if so, water can be easily introduced at several points around the circumference of the entrance to the crushing stage in which water is to be introduced.

It is to be understood that in a crusher built according to my invention, the shape or profile of the crushing surfaces, the depth of the crushing surfaces of each stage, the angle between the crushing surfaces of the head and concaves of each stage, and the diameters of head and concaves of each stage may all be varied to suit the particular material that is to be crushed.

Also, the slope of the guiding surfaces which convey the material from the discharge of one crushing stage into the opening of the succeeding stage may be varied to suit the particular material to be crushed and whether the material is crushed wet or dry.

In the preceding subject matter and in the appended claims the expressions "equal active discharge area" and "discharging an equal weight of material in an equal interval of time" have been used in connection with the proper design of the various stages of the crusher. In the preceding subject matter the expression "equal active discharge area" has been explained and illustrated and as there explained this expression does not mean that the physical discharge openings of the various stages are of equal area. The expression "discharging an equal weight of material in an equal interval of time" is used to describe a feature of construction of the crusher of the present application which is not found in prior crushers. That is suppose the first stage of a multi-stage crusher designed according to this invention is to have a capacity of 100 tons of material per hour crushing material say from 5" size to 2" size when this first stage is crushing material alone as a single stage crusher. Suppose now a second stage is added to crush the material from 2" size to $\frac{3}{4}$ " size. It should have a capacity of 100 tons per hour when this second stage operates entirely independently. Let us suppose that a third stage is added to crush the material from $\frac{3}{4}$ " size to $\frac{1}{4}$ " size. It should therefore also have a capacity of 100 tons per hour when it would be operating alone and independently of any of the other stages. Hence all three stages are designed for "discharging an equal weight of material in an equal interval of time".

If however we would add to the first stage of this crusher having a capacity of 100 tons an hour a second stage which only has a capacity of 80 tons an hour it would choke back the first stage so that it too would only deliver 80 tons an hour and if the third stage is added with a capacity of only 60 tons an hour it would choke back the material of the second stage to 60 tons an hour and the second stage would then permit only a discharge of 60 tons an hour from the first stage. However, in the latter case although all three stages are discharging 60 tons an hour in equal intervals of time the stages previous to the third stage are not operating at their full capacity. The first example in which all three stages operate at their full capacity and discharge 100 tons of material an hour is considered the proper proportioning of all three stages according to the present invention and the second case where the crusher capacity was only 60 tons an hour due to the limitations existing in the third stage of the crusher should be considered an improper proportioning of the crusher according to my invention. Or in a two-stage crusher where the first stage has an individual capacity of 100 tons an hour and in the second stage of only 80 tons an hour is also an improper proportioning of a multi-stage crusher according to my invention.

tion. Hence the term "discharging an equal weight of material in an equal interval of time" refers to the full capacity of each stage of the crusher when there is no choking and decreasing the capacity of a previous stage due to too small a capacity of a succeeding stage. The present invention therefore consists in arranging, proportioning and constructing all the stages of a multi-stage crusher so that each stage has the same capacity of any of the other stages when they are operating independently of each other. The present invention also consists in the provision of conveying surfaces between stages which will deliver the material from one stage to the succeeding stage in such manner as to facilitate the effective continuous operation of the entire machine and deliver the material from the smaller diameter crushing head to the successive larger diameters of the crushing heads.

20 In accordance with the provisions of the patent statutes, I have described the principle of operation of my invention together with the apparatus which I now consider to represent the best embodiments thereof; but I desire to have it understood that the apparatus shown is only 25 illustrative, and that the invention can be carried out by other means.

What I claim as new and desire to secure by Letters Patent of the United States, is:

30 1. A gyratory crusher having two or more crusher heads mounted on a gyrating shaft and having each crusher head surrounded by a suitable stationary concave so arranged and constructed that each crusher head together with its corresponding concave form a definite crushing stage so that the material to be crushed passes successively from one crushing stage to another where it is consecutively crushed to a finer size, and having each successive crushing 35 stage so designed and constructed that it has its entire crushing surfaces at substantially greater diameters than those of the preceding stage, and having movable non-crushing means for conveying the material to be crushed from one stage of small diameter to the succeeding 40 stage of materially larger diameter.

2. A gyratory crusher having two or more crushing heads of progressively and substantially larger diameters, mounted on a gyrating shaft, 45 each crusher head surrounded by suitable stationary concaves so as to form definite crushing stages, and having every part of the crushing surfaces of each crushing stage of a larger diameter than any part of the crushing surfaces of the preceding stage, and so designed and constructed that the material to be crushed passes through the crushing stages in sequence from the smallest diameter stage to the next larger one, and having the active discharge areas of 50 all stages substantially equal.

3. A gyratory crusher having crushing surfaces mounted on a gyrating shaft and having stationary crushing surfaces surrounding them and so designed and constructed that the material to be crushed passes between the gyrating and stationary crushing surfaces in an approximately vertical direction, and in which the crushing is performed in successive stages having greatly increased diameters and also greatly increased 55 crushing areas than those of the preceding stage, and having the discharge areas of all the stages so proportioned that equal weights of material pass through them in equal intervals of time, and movable means for conveying the material 60 to be crushed from the discharge opening of one

stage to the inlet opening of the succeeding stage.

4. A gyratory crusher having two or more heads mounted on a common gyrating shaft, each head surrounded by stationary concaves and so designed and constructed as to form definite crushing stages, each succeeding stage being of a considerably greater diameter than that of the preceding stage, and inclined conveying surfaces between each crushing stage for conveying material to be crushed from one stage to another.

5. A gyratory crusher embodying a plurality of gyrating crushing surfaces to crush material in successive stages and having the discharge opening of each stage of less diameter and greater 15 width than those of the discharge opening of the succeeding stage, and said gyrating crushing surfaces being of such size and proportions with respect to said discharge openings that all of the discharge openings will always have approximately active equal discharge areas, and inclined non-crushing conveying surfaces between said stages for conveying material from one stage to the succeeding stage.

6. In a gyratory crusher, a series of concaves, 25 gyrating crushing means cooperating with said concaves and including a plurality of crushing heads having their crushing surfaces inclined with respect to the vertical axes, said crushing means including conveying surfaces between said crushing heads, said conveying surfaces inclined at angles to their vertical axes greater than the angles of inclination of said crushing surfaces.

7. In a gyratory crusher, a movable crushing member comprising alternate crushing and conveying surfaces, said crushing surfaces being arranged to crush material in successive stages, the crushing surface of each stage being of predetermined proportional greater diameter than that of the crushing surface of the preceding stage, said 40 crushing surfaces being inclined, said conveying surfaces being inclined at relatively flatter degrees of inclination with respect to the horizontal than the degrees of inclination of the crushing surface.

8. In a gyratory crusher, a frame, a plurality of concaves carried by said frame, a plurality of movable crushing heads arranged to co-operate with said concaves to crush material in successive stages and form with said concaves discharge openings for each stage, a motor for driving said 50 crushing heads, conveying surfaces between said heads and spaced from the frame a distance greater than the maximum width of the adjacent discharge opening whereby the conveying surfaces will be non-crushing, said crushing surfaces being inclined, said conveying surfaces being inclined at relatively flatter degrees of inclination with respect to the horizontal than the degrees of inclination of the crushing surfaces.

9. A gyratory crusher having stationary crushing surfaces and movable crushing surfaces between which material is crushed, said crushing surfaces so arranged that the material is crushed successively in two or more definite crushing stages, the gyrating and stationary crushing surfaces of the initial stage being so dimensioned and proportioned and so arranged with respect to each other as to crush a definite quantity of material to or smaller than a predetermined definite size in a definite interval of time, the crushing 65 surfaces of each successive stage being of larger diameter than the crushing surfaces of the preceding stage and proportioned and arranged with respect to each other and to the crushing surfaces of the preceding stage so as to crush at least the 70

- same quantity of material to or smaller than a predetermined definite size in an equal interval of time, as required by the preceding stage, said crushing surfaces being inclined, gyrating conveying surfaces between the movable crushing surfaces of the crushing stages, said conveying surfaces being inclined at relatively flatter degrees of inclination with respect to the horizontal than the

degrees of inclination of the crushing surfaces whereby the material being crushed will be caused to make an abrupt turn in its direction of travel in passing from one crushing stage to the succeeding stage for causing a spreading of the material over the gyrating conveying surface. 5
